UNITED STATES PATENT OFFICE.

ARTHUR L. STANFORD, OF CHICAGO, ILLINOIS.

RAIL-ANCHOR.

1,129,816.

Specification of Letters Patent. Patented Feb. 23, 1915.

Application filed January 7, 1914. Serial No. 810,853.

To all whom it may concern:

Be it known that I, ARTHUR L. STANFORD, a citizen of the United States, residing at Chicago, in the county of Cook and State 5 of Illinois, have invented certain new and useful Improvements in Rail-Anchors, of which the following is a specification.

The device of the present invention relates to an article used in conjunction with 10 railway rails for the purpose of anchoring the said rails and preventing what is known as the creeping thereof.

One of the objects of the present invention is to produce a device of the character 15 specified which will be automatic in its action; that is, which will increase its gripping force upon the rail in proportion and in correspondence to the force of the strain exerted tending to cause the rail to creep.

20 Further objects of the invention are to provide the anchor with an auxiliary holding device which will serve to bind one side of the anchor to the rail, whereby the creeping action of the rail will move the opposite 25 sides of the anchor in opposite directions around a center of movement, and thus increasing its position of angularity, and increasing its gripping action to resist creeping of the rail; to produce a device which is

30 of a unitary or one-piece construction with the exception of the overhanging portion of one jaw; to provide a simple and efficient means for creating the auxiliary hold upon the rail referred to, which means will serve 35 as an overhanging portion of one jaw; to form a tie-abutting member, as well as the gripping surfaces of the anchor, of a curvilinear formation, making substantial contact between the gripping surfaces of the 40 anchor and the rail at all times; to form the device in a manner whereby it is cheap and simple of manufacture and easy of installation; to so configure the body of the anchor as to enable it to assume its canting or 45 oblique position without interference by contact with the tie; and to so form the auxiliary holding device as to have it increase its hold as the rail tends to move.

The invention further consists in the features of construction and combinations of parts hereinafter described and claimed.

In the drawings: Figure 1 is a vertical section of a rail with the anchor of the present invention in operative position thereon; 55 Fig. 2 is a plan view showing the rail and anchor in the position they assume when ini-

tially installed; Fig. 3 is a view similar to Fig. 2 showing the anchor in the position it assumes when thrown to a canting or clamping position; Fig. 4 is a section on line 4—4 60 of Fig. 1 looking in the direction of the arrows; Fig. 5 is a perspective of the body portion of the anchor; and Fig. 6 is a perspective of the auxiliary holding member.

In the art to which the present invention 65 relates, it is the design of the various devices to prevent what is known as the creeping of the rail, such creeping, owing to an unexplained phenomenon, being in the direction of travel of the rolling stock over the rail. 70 The undesirability of such creeping is well known to those conversant in railroad work, and the desirability of means for preventing such creeping is acknowledged.

The anchor of the present invention, as before briefly stated, is intended to be of the 75 form or nature which is automatic in its action; that is, it assumes a position whereby its holding or clamping action on the rail is increased automatically and in proportion 80 to the strain or force exerted on the rail, tending to produce the creeping action, whereby the greater the force exerted the greater will be the resisting action of the anchor to counteract such force.

85 Referring to the drawings, and particularly to Fig. 1, the device is illustrated in connection with a rail 7 of the usual and well known type. The anchor consists of a body portion 8 composed of a horizontally 90 extending plate-like section 9 which underlies the base of the rail and extends transversely of the rail, and the section 9 terminates in one end in a jaw 10 having an overhanging portion 10^a adapted to extend 95 and engage the upper face of the base of the rail, and the opposite end of the section 9 terminates in an upwardly extending lug 11 which has a recess 12 therethrough, the function of which will be more clearly hereinafter explained. Depending from the section 9 are vertically extending strengthening flanges 13, a portion 14 of one of which is larger than the remainder, and forms the rail-abutting portion of the device. A rail-gripping surface 15 is located at one end of the section 9 and is a portion of the jaw 10, and a rail-gripping surface 16 is located at the opposite end of the said section and is a portion of a jaw 16^a. These rail-gripping surfaces 15 and 16 are arranged and adapted to engage the side edges of the 100 105 110

base of the rail, and, as shown in Figs. 2, 3, and 4, are curvilinear in formation. As will be observed from the drawings, one portion of one side 17 of the body of the anchor is cut away, reducing the transverse dimension of the anchor at one end thereof, which permits the anchor to move into the diagonal position necessary to effect the rail-anchoring function. The recess 12 in 5 the lug 11 receives a circular portion 18 of an auxiliary holding device 19, which device is in the form of a pin or stem, and consists of the circular portion 18, an eccentric head 20, and a polygonal-shaped end 21, 10 which latter end may be in the form of an integral portion of the pin or stem, as in Figs. 1, 2, and 6, or may consist of a nut threaded onto the stem, as in Fig. 3. In fact any surface is contemplated which is 15 capable of receiving some suitable form of tool or wrench for turning the said holding device.

To place the anchor in position upon the rail, the stem or pin 19 is removed and the anchor slipped in place in an obvious manner. The pin or stem is then repositioned and the device will then appear as in Fig. 2, and when the stem or pin 19 is so positioned, it will constitute the overhanging 20 portion of the jaw 16^a performing in this respect the same function as the overhanging portion 10^a. When this has been done, the anchor is driven by a suitable driving tool into slanting or diagonal position, as 25 in Fig. 3. This will tend to cant the device in a manner whereby the gripping surfaces 15 and 16 will be brought into biting engagement with the sides of the rail flanges, as will be obvious from the drawings. When 30 the anchor has been thus positioned, an initiatory grip is placed upon the rail, which is sufficient to enable the anchor to operate at once to resist the creeping tendency. After the anchor has been so positioned, the pin or stem 19 will be turned so as to bring the eccentric head 20 into a 35 firm engagement with the upper surface of the base of the rail. This will create an auxiliary hold upon the rail at this point, 40 so that the anchor will obtain a firmer initiatory hold upon that side of the rail than upon the opposite side. It is, of course, not contemplated that this holding device will in any way serve materially to hold the rail 45 against creeping. Its function and office is as follows: When the strain comes upon the rail tending to make it creep, the tie-abutting surface 14 being already in engagement with the tie, the side of the anchor upon 50 which such tie-abutment is located cannot move with the rail, so there is a positive stop on this side of the anchor. The other side of the anchor, however, is free to move with the rail, and the auxiliary-holding device is provided on this side to insure its 55 moving with the rail, so there is one side of the anchor held against movement with the rail, and the other side moving with the rail. The result will be a swinging movement of the anchor about the point of engagement of the tie-abutment with the tie; that is, the tie-abutment will rock on the face of the tie, whereby the anchor will assume a greater degree of angularity. This 60 will result in an increase in the gripping action of the anchor, and obviously the more strain exerted tending to carry the aforesaid one side of the anchor forward, the greater will be the gripping action of the rail-gripping surfaces, due to the increased 65 position of angularity of the anchor. The above described characteristics of the device make the action of the anchor automatic.

By reason of the curvilinear surfaces of the rail-gripping devices and the rail abutting member, the point of engagement between the abutting member and the tie, and the point of engagement between such gripping surfaces and the rail will change but little; that is, all of these surfaces being 70 curvilinear they will rock along the surfaces with which they engage, whereby the action will be smooth and the extent of engagement between such members and such surfaces will be changed but slightly. That 75 is, the curvilinear gripping surfaces insure a sufficient amount of contact between the gripping surfaces and the rail at all times to insure a sufficient grip, the degree of contact between the gripping surfaces and the rail never reaching such a small degree as to impair the efficiency of the gripping action. The arrangement of the head 20 is such, as 80 will be obvious from the drawings, as to cause said head to rotate as the rail moves, 85 and hence brought into firmer engagement with the rail. The device is, of course, susceptible of modification without departing from the spirit of the present invention, provided it is maintained within the scope 90 of the appended claims.

I claim:

1. In a rail anchor, the combination of a body portion having opposed rail gripping surfaces, and a tie abutment formed integral therewith, a rotatable non-resilient auxiliary holding device carried upon one side of the body portion and adapted to engage the upper face of the base of the rail and bind that side of the anchor to the rail, and said holding device having its center of rotation extending substantially parallel to the slope of the upper face of the base of the rail, substantially as described.
2. In a rail anchor, the combination of a body portion embodying a tie abutment and opposed rail-gripping surfaces, and a non-resilient auxiliary holding device carried upon the opposite side of the said body portion from that on which the tie abutment is

- located, said holding device being adapted to engage the upper face of the base of the rail and bind that side of the anchor to the rail, said body being of decreased width at 5 that side upon which said auxiliary holding device is located, whereby such side is held free from engagement with the tie, substantially as described.
3. In a rail anchor, the combination of a body portion embodying rail-gripping surfaces and a tie abutment, and a non-resilient auxiliary holding device carried upon one side of the body portion embodying an eccentric head arranged to bear against the 10 upper face of the rail base and bind that side of the anchor to the rail, and said holding device having a horizontally disposed axis of rotation, substantially as described.
4. In a rail anchor, the combination of a body portion embodying a tie abutment and opposed rail-gripping surfaces, a non-resilient auxiliary holding device carried upon one side of said body portion and embodying an eccentric head adapted to engage the 15 upper face of the rail base and bind that side of the anchor to the rail, said body being of decreased width at that side upon which said auxiliary holding device is located, substantially as described.
5. In a rail anchor, the combination of a body portion embodying rail-gripping surfaces and a tie abutment, an upwardly extending lug upon one side of said body portion, a stem rotatably mounted in said lug 20 terminating at one end in an eccentric head arranged to engage the upper surface of the rail base and terminating at its other end in a polygonal surface to receive an operating tool, said head constituting a non-resilient auxiliary holding device for binding one side of the anchor to the rail, substantially as described.
6. In a rail anchor, the combination of a body portion embodying rail-gripping surfaces and a tie abutment, an upwardly extending lug upon one side of said body portion, a stem rotatably mounted in said lug 25 terminating at one end in an eccentric head arranged to engage the upper surface of the rail base and terminating at its other end in a polygonal surface to receive an operating tool, said head constituting a non-resilient auxiliary holding device for binding one side of the anchor to the rail, substantially as described.
7. In a rail anchor, the combination of a body portion embodying curved rail-gripping surfaces and a curved tie abutment, and a non-resilient auxiliary holding device carried upon one side of the body portion 30
- tion and adapted to engage the upper surface of the rail base to bind one side of the anchor to the rail, substantially as described. 65
8. In a rail anchor, the combination of a body portion embodying curved rail-gripping surfaces and a curved tie abutment, and a non-resilient auxiliary holding device carried upon one side of the body portion 35 and adapted to engage the upper surface of the rail base to bind one side of the anchor to the rail, said body being of decreased width at that side upon which said auxiliary holding device is located, substantially as described. 75
9. In a rail anchor, the combination of a body portion embodying curved rail-gripping surfaces and a curved tie abutment, an upwardly extending lug upon one side of said body portion, a stem rotatably mounted in said lug, and terminating at one end in an eccentric head arranged to engage the upper surface of the rail flange and terminating at its other end in a polygonal 40 surface to receive an operating tool, said head constituting a non-resilient auxiliary holding device for binding one side of the anchor to the rail, substantially as described. 85
10. In a rail anchor, the combination of a body portion embodying curved rail-gripping surfaces and a curved tie abutment, an upwardly extending lug upon one side of said body portion, a stem rotatably mounted in said lug, and terminating at one end in an eccentric head arranged to engage the upper surface of the rail flange and terminating at its other end in a polygonal 45 surface to receive an operating tool, said head constituting a non-resilient auxiliary holding device for binding one side of the anchor to the rail, said body being of decreased width at that side upon which said auxiliary holding device is located, substantially as described. 90
11. In a rail anchor, the combination of a body portion, oppositely disposed jaws, a tie abutment integral with the body, opposed rail-gripping surfaces embodied in said jaws and formed integral with the body 50 portion, a one piece rotatable non-resilient auxiliary holding device on one side of the anchor, said holding device having its center of rotation extending substantially parallel to the slope of the upper face of the rail 55 base, said holding device forming the overhanging portion of one of said jaws, the overhanging portion of the other jaw being integral with the body, substantially as described. 105
